UNITED STATES PATENT OFFICE.

ARNOLD AUGUST EGLI, OF BERN, SWITZERLAND, ASSIGNOR TO POLYGRAPHISCHE GESELLSCHAFT, OF LAUPEN-BERN, SWITZERLAND.

PLATEN SETTER.

Application filed January 13, 1923. Serial No. 612,369.

To all whom it may concern:

Be it known that I, ARNOLD AUGUST EGLI, a citizen of the Swiss Republic, residing at Bern, Switzerland, 7 Bitziusstrasse, have invented certain new and useful Improvements in Platen Setters, of which the following is a specification.

This invention relates to paper feed devices or platen stepping devices for printing machines, more particularly for machines in which the paper with the platen is moved into contact with a line of types that has been previously set for printing.

In accordance with the invention the platen is directly or indirectly connected with a ratchet wheel whose stepping pawl is caused to impart more or less rotary movement to the wheel according to the adjustment of an adjustable stop against which the pawl or a part connected with it abuts. The ratchet wheel is preferably connected with a worm that engages with a worm wheel arranged on the shaft of the platen. The relative positions of the worm and the worm wheel could, however, be reversed to accomplish the same result. The pawl is preferably linked to a lever equipped with a roll that strikes against the said adjustable stop. The adjustable stop may be mounted on a curved bar whose curvature corresponds to the curved path described by the platen. The ratchet is preferably provided with a handle and the worm wheel is arranged in a known manner so as to be detachable from the platen.

The invention is illustrated in the drawing in which—

Fig. 1 is a side elevation and

Fig. 2 a plan view.

Referring to the drawing *a* is a platen upon whose shaft a worm wheel *b* is arranged that engages with a worm *c*. The worm *c* and a ratchet wheel *d* are mounted on a common shaft journaled in a frame or bracket supported by an arm or the like which rotates freely around the platen shaft. A pawl *f* co-operates with the ratchet wheel *d*. The pawl *f* is pivoted on a lever *g* equipped with a roll *h*. The lever *g* is acted upon by a spring *r* which tends to rotate the lever *g* into contact with a stop *i*. *k* is a curved graduated bar with a slot *k'* adapted to receive a screw with a thumb nut *n* for fixing an adjustable stop *m*. The curvature of the curved bar *k* or support

for the stop *m* corresponds to the curve described by the platen when it is rocked into the printing position shown in broken lines in Figs. 1 and 2.

The device operates in the following manner: When the platen is rocked from the normal position into the printing position the arm or lever *g*, on leaving the adjustable stop *m* is rotated backwards by the spring *r* until it strikes against the stop *i*. During this backward rotation of the arm *g*, that takes place when the platen is rocked forward, the pawl *f* trails over the teeth of the ratchet wheel *d*. When the platen *a* is swung back into its normal position the roll *h* of the arm *g* strikes against the stop *m* and the arm *g* is then rotated away from the stop *i* until the pawl *f* reaches its normal position in which it is shown in solid lines in Figs. 1 and 2. When it is thus rotated back from the position in which it strikes against the stop *i* into its normal position the arm *g* by means of the pawl *f* turns the ratchet wheel *d* and this rotation is transmitted through the worm *c* to the worm wheel *d* and through this latter to the platen *a*.

The worm wheel *d* is slipped onto the shaft of the platen *a* and is arranged to be fixed to the same by means of a small hand wheel *o*. The ratchet wheel is also provided with a handle *p* by means of which the wheel can be turned through any angle for the purpose of adjusting the platen *a*.

Claims:

1. In a printing machine, types, a platen, a platen rocker for moving the platen onto the types, a paper feeding device, a ratchet wheel associated with the paper feeding device, a pawl for rotating the ratchet wheel, movement reducing means interposed between the ratchet wheel and the paper feeding device, and a stop against which the said pawl abuts.

2. In a printing machine, types, a platen, a platen rocker for moving the platen onto the types, a paper feeding device, a ratchet wheel associated with the paper feeding device, a pawl for rotating the ratchet wheel, a movement reducing gear interposed between the ratchet wheel and the paper feeding device, and a stop against which the said pawl abuts.

3. In a printing machine, types, a cylindrical platen, a platen shaft, a platen rocker

for swinging the platen onto the types, a ratchet wheel associated with the platen, a pawl for rotating the ratchet wheel, a worm and a worm wheel for transmitting the rotation of the ratchet wheel to the platen, and an adjustable stop against which the said pawl abuts.

4. In a printing machine, types, a cylindrical platen, a platen rocker for swinging the platen onto the types, a ratchet wheel associated with the platen, a pawl for rotating the ratchet wheel, a roll associated with the pawl, and a stop against which the roll abuts.

5. In a printing machine, types, a cylindrical platen, a platen rocker for swinging the platen onto the types, a ratchet wheel associated with the platen, a pawl for rotating the ratchet wheel, means for rotating the pawl relatively to the ratchet wheel, a stop against which the said pawl abuts, and another stop for limiting the motion of the said pawl.

6. In a printing machine, types, a cylindrical platen, a platen rocker for swinging the platen onto the types, a ratchet wheel associated with the platen, a pawl for rotating the ratchet wheel, means for rotating the pawl relatively to the ratchet wheel, a stop against which the said pawl abuts, and a curved support carrying the said stop.

7. In a printing machine, types, a platen, a platen rocker for moving the platen onto the types, a paper feeding device, a ratchet wheel associated with the paper feeding device, a pawl for rotating the ratchet wheel, a worm gear interposed between the ratchet wheel and the paper feeding device, and a stop against which the said pawl abuts.

8. In a printing machine, types, a cylindrical platen, a platen shaft, a platen rocker for swinging the platen onto the types, a ratchet wheel associated with the platen, a pawl for rotating the ratchet wheel, a worm and a worm wheel for transmitting the rotation of the ratchet wheel to the platen, an adjustable stop against which the said pawl abuts, and means for rendering the said transmitting means inoperative.

9. In a printing machine, types, a cylindrical platen, a platen rocker for moving the platen onto the types, a paper feeding device, a ratchet wheel associated with the paper feeding device, a pawl for rotating the ratchet wheel, a movement reducing

means interposed between the ratchet wheel and the paper feeding device, and a stop against which the said pawl abuts.

10. In a printing machine, types, a platen, a platen rocker for moving the platen onto the types, a paper feeding device, a ratchet wheel associated with the paper feeding device, a pawl for rotating the ratchet wheel, an adjustable stop against which the pawl abuts, and a movement reducing means interposed between the ratchet wheel and the paper feeding device.

11. In a printing machine, types, a cylindrical platen, a platen rocker for swinging the platen onto the types, a ratchet wheel associated with the platen, a pawl for rotating the ratchet wheel and adapted to be moved with the platen, means for rotating the pawl relatively to the ratchet wheel, a first stop against which the said pawl abuts, and second stop for limiting the motion of the said pawl, when the platen is moved onto the types.

12. In a printing machine, types, a platen, a platen rocker for swinging the platen onto the types, a ratchet wheel associated with the platen, a pawl for rotating the ratchet wheel, means for rotating the pawl relatively to the ratchet wheel, an adjustable stop against which the said pawl abuts, and a curved support carrying the said stop.

13. In a printing machine, types, a cylindrical platen, a platen shaft, a platen rocker for swinging the platen onto the types, a ratchet wheel associated with the platen, a pawl for rotating the ratchet wheel, and a pawl carrier adapted to be swung round the axis of the said wheel.

14. In a printing machine, types, a cylindrical platen, a platen shaft, a platen rocker for swinging the platen onto the types, a ratchet wheel associated with the platen, a pawl for rotating the ratchet wheel, an adjustable stop against which the said pawl abuts, and a spring adapted to move the pawl carrier relatively to the ratchet wheel.

In testimony whereof I have affixed my signature in presence of two witnesses.

ARNOLD AUGUST EGLI.

Witnesses:

WERNER SCHAEFFER,
R. HEINGARTNER.
